UNITED STATES PATENT OFFICE.

FRANK O. MILLER, OF YOUNGSTOWN, OHIO.

SELF-DUMPING MACHINE FOR BLAST-FURNACES, &c.

SPECIFICATION forming part of Letters Patent No. 615,730, dated December 13, 1898.

Application filed October 26, 1897. Serial No. 656,462. (No model.)

To all whom it may concern:

Be it known that I, FRANK O. MILLER, a citizen of the United States of America, residing at Youngstown, in the county of Mahoning and State of Ohio, have invented certain new and useful Improvements in Self-Dumping Machines for Blast-Furnaces and the Like, of which the following is a specification, reference being had therein to the accompanying drawings.

This invention relates to certain new and useful improvements in self-dumping machines for blast-furnaces and the like, and has for its object to provide means for loading ore, coke, lime, or any material of like nature into the dump-bucket at the bottom of the elevator-shaft and hoisting to the top of the same, where it is carried to a point over the hopper and automatically dumped into the same.

The principal features of my invention consist in an inclined track, upon which operates a truck carrying a plate which is adapted to automatically grip and hold the line by which the dumping-bucket is operated. This plate retains its grip upon the line until the bucket is carried to the desired point over the hopper and until the dump-bucket is again lowered to the end of the track, where the grip is automatically released, so as to permit the bucket to descend into the elevator-shaft.

To this end the invention consists in the novel construction, combination, and arrangement of parts to be hereinafter more specifically described, and particularly pointed out in the claims.

In describing the invention in detail reference is had to the accompanying drawings, forming a part of this specification, and where 40 in like letters of reference indicate similar parts throughout the several views, in which—

Figure 1 is a side elevation, partly in section. Fig. 2 is a perspective view of the dump-bin and a portion of the chutes. Fig. 3 is a front view. Fig. 4 is a horizontal sectional view taken on a line above the dump-bin. Fig. 5 is a perspective view of the guard-plate of the carrier. Fig. 6 is a perspective view of the hanger carried by the operating-line. Fig. 7 is a plan view of a portion of the plate. Fig. 8 is a side view of the same. Fig. 9 is a cross-sectional view of the same.

The frame for supporting the track may be of any desired construction and in the drawings is shown as composed of four supporting- 55 columns *a a* and *b b*, which are in the form of ordinary I-beams. Arranged in front of the columns *a* is a dump-bin *c*, having chutes *d*, which rest upon and are secured to a cast block *f*, supported by a pin *g*, carried by a 60 hanger *h* of the bell *k*, the said bell operating within an ordinary hopper *l*, and the hanger *h* of the bell being connected to the walking-beam *m*, which is pivotally supported at its center by a supporting-post *n*, which also carries the pulley *o* to receive the operating cord or belt *p*. This belt passes around the pulley-wheel *q*, mounted on top of the hanger *h*, and over the pulley-wheel *r*, which is suitably supported over one of the supporting-columns *b*. 70 This pulley-wheel *r* is preferably a double one, in order that the cord or belt *s*, connecting with the pulley on the engine, may also be attached thereto. By crossing the belt or cord *p*, which is attained by means of the pulley *o*, the dump- 75 bin and chutes are turned one-quarter way round by each reversing of the engine, so that the charge within the dump-bin will be evenly distributed over the bell.

Supported by the columns *a* is a suitable 80 track *a'*, which is arranged at an angle of about forty-five degrees, with the lower end of the same at a point between the columns *b* and directly over the elevator-shaft. The lower ends of the rails forming this track are 85 turned upwardly, so as to form a stop for the carrier, which rides on the track, the said rails being supported by a hanger which is connected to the cross-piece *a²*, connecting the two rails together. 90

The carrier consists of the two wheels *b'*, which are mounted upon a common axle *b²*, which also has centrally mounted thereon a pulley *b³* to receive the operating-rope *c'*, this rope also passing over the pulley *c²*, mounted 95 upon an axle secured near the upper end of the track-rails and is attached at its lower end to a hanger *c³*, having a recess *c⁴*, and to which hanger is attached a holder *d'*, which carries the dump-bucket *d²*. Fulcrumed to 100 the axle *b²*, upon which the track-wheels *b'* are mounted, are outwardly-extending hook-arms *d³*, which are adapted to engage upon a bolt *d⁴*, passing through the lower or curved ends

of the track-rails a' when the carrier is in the lowered position. Also fulcrumed to this axle b^2 are links e' , which carry the guard-plate e^2 , which is provided with an aperture e^3 , through which the carrying-rope c' passes. Secured on the underneath face of this guard-plate are suitable cleats e^4 , forming a guide for the plate f' , which is adapted to slide between said cleats and provided at its forward end 10 with a recess f^2 to receive the carrying-rope c' . This plate f' is operated by means of an arm f^3 , passing through an elongated slot f^4 of the carrier-plate e^2 and attached to the plate f' , said arm f^3 having a weighted extension f^5 and being supported by means of arms f^6 , fulcrumed to the axle b^2 and connected by a cross-rod f^7 . The bucket d^2 is retained in position for filling by means of a lever g' , having a hook end g^3 to engage over the bucket 20 and which is released from its engagement by the lever riding against a connecting-bar g^3 , attached to the two track-rails a' at a point directly above the dump-bin c .

When the carrier has been lowered to the end of the track and at which point it is directly over the elevator-shaft, the arms f^3 , coming into engagement with the cross-rod d^4 , are lifted so as to release the plate f' out of its engagement in the recess c^4 of the hanger 30 c^3 , and thus permit the bucket to descend into the elevator. When filled and again hoisted, the horns h' , which are provided on the holder d' , come into engagement with the hook-arms d^3 , so as to lift the same and allow the carrier 35 to be moved upward on the inclined track by means of the carrier-cord c' . This upward movement of the carrier removes the arms f^3 from their resting-place upon the cross-rod d^4 and permits the weighted end f^5 of the said 40 arms to operate that portion f^3 thereof, so as to again force the plate f' into the recess c^4 of the bucket-hanger, thus locking the bucket securely in this position, where it is held until it is carried to the point directly 45 over the dump-bin, at which time the lever g' is disengaged from the bucket by its action against the connecting-bar g^3 and the bucket tilted, so as to permit the emptying of its contents into the dump-bin c . When 50 the engine is reversed, this dump-bin and its chutes are given one quarter-turn by means of the connecting belt or cord p , and the ore, lime, or other material which has been dumped

into the bin is thereby evenly distributed over the bell of the hopper.

55

I desire to call particular attention to the construction of the carrier-plate, which enables the locking of the carrying-rope in such a manner as to retain the dump - bucket in the upright position until the point is reached 60 at which it is desired to deliver the load of the bucket, and also to the automatic means by which the plate f' is released and the carrying-cord permitted to operate through the carrier - plate, so as to permit the bucket to 65 descend into the elevator-shaft. It will also be noted that various changes may be made in the details of construction without departing from the general spirit of my invention.

Having fully described my invention, what 70 I claim as new, and desire to secure by Letters Patent, is—

1. In combination with a hopper, a receiving-bin, oppositely-disposed chutes carried by said bin, a walking-beam, a bell secured to a 75 hanger and supported by said walking-beam, a pulley supported by said hanger and secured to said receiving - bin, means engaging said pulley whereby the bin and chutes are caused to reciprocate, and a traveling carrier arranged 80 above said bin, substantially as shown and described.

2. In combination with a hopper, a receiving-bin, chutes carried by said receiving-bin and arranged opposite each other, a walking- 85 beam, a bell suspended from said beam, said walking-beam carrying a pulley, connections between the pulley and engine, whereby the receiving - bin and chutes are oscillated to evenly distribute the ore in the hopper, a 90 track and carrier arranged above said receiving-bin, a guard-plate carried by said carrier, said guard-plate being provided with an aperture through which the operating-rope passes, a weight - actuated plate carried by 95 said guard-plate whereby said operating-rope is locked when the carrier is brought over the receiving-bin and unlocked when returned to a position over the elevator - shaft, substantially as shown and described.

In testimony whereof I affix my signature in presence of two witnesses.

FRANK O. MILLER.
